Primary Examiner — Mary Ann Calabrese(74) *Attorney, Agent, or Firm* — Woodard, Emhardt,
Henry, Reeves & Wagner, LLP(57) **CLAIM**

The ornamental design for a desk, as shown and described.

DESCRIPTION

FIG. 1 is a top plan view of a desk showing my new design,
shown in a stored position of use;

FIG. 2 is a front elevation view thereof;

FIG. 3 is a top perspective view thereof;

FIG. 4 is a top plan view thereof, shown in an open position
of use;

FIG. 5 is a front elevation view thereof;

FIG. 6 is a top perspective view thereof; and,

FIG. 7 is a bottom perspective view thereof.

Portions of the desk illustrated with broken lines form no
part of the claimed design.**1 Claim, 7 Drawing Sheets**(56)
